(57) **CLAIM**

The ornamental design for a carrier board of pallet trolley as shown and described.

DESCRIPTION

FIG. 1 is a top perspective view of a carrier board of pallet trolley showing my new design;

FIG. 2 is a front elevational view thereof;

FIG. 3 is a rear elevational view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a bottom perspective view thereof; and,

FIG. 9 is a top perspective view.

The broken lines in FIG. 9 are for the purpose of illustrating an environment of the design only, and form no part of the claimed design.
